UNITED STATES PATENT OFFICE.

FRANK HADFIELD ARNOTT, OF LONDON, ENGLAND.

CARBURETOR.

Application filed August 9, 1921. Serial No. 490,986.

To all whom it may concern:

Be it known that I, FRANK HADFIELD ARNOTT, a subject of the King of Great Britain and Ireland, and residing at Willesden Green, London, N. W. 10, England, have invented certain new and useful Improvements in and Relating to Carburetors, of which the following is a specification.

This invention relates to carburetors for 10 internal combustion engines and more particularly to the type wherein the main supply of air is automatically controlled.

The object of the invention is to provide 15 a carburetor which will deliver automatically to the engine a correctly proportioned mixture of fuel and air at all degrees of opening of the throttle valve.

The invention consists in the combination 20 and arrangement of parts and details of construction hereinafter described and claimed, it being understood that changes in the embodiment of the invention herein disclosed may be made within the scope of the claim, without departing from the spirit 25 of the invention.

An example of a carburetor according to the invention is illustrated in the accompanying drawings, of which:

Figure 1 is a diagrammatic sectional elevation, and

Figure 2 is a modification of the spring control mechanism of Figure 1.

As shown in the drawings, the carburetor includes a float chamber A having a known 35 constant level device for the fuel, sealed from the atmosphere, and integral with an extension B. The upper part of B has a cylindrical bore which is closed at the top by a bobbin-shaped plug C screwed or otherwise 40 fastened therein. This plug is bored axially and forms a guide for a push rod D whose upper end extends through the plug C and whose lower end bears upon the piston-shaped head G of a tapered needle 45 valve H.

The piston G slides freely in the cylindrical bore of B and the combination acts as a dashpot to steady the movement of the needle valve in a jet orifice P formed in the 50 lower part of B. This lower part of B is formed with a cylindrical outer surface surrounding the jet orifice P.

An extension W, surrounding and coaxial

with the cylindrical lower part of B, forms a mixing chamber and a pipe V leads from 55 this chamber through a throttle valve T to the engine. The lower end of the chamber W has an internally threaded orifice into which an externally threaded tubular part M is fitted. The upper inner surface of the 60 part M is chamfered conically and provides a seat for a combined air and fuel valve K. This valve is formed as a hollow cylinder open at its upper end and closed at its base excepting for a series of holes or 65 ports L. A downward projecting part of the needle valve H extends beyond the orifice P to a point adjacent to the base of the valve K and exact adjustment of the relative positions of the valve K and needle 70 valve H may be accomplished by adjusting the part M in which the valve K seats upwardly or downwardly. A short parallel portion of the valve K of slightly reduced diameter below the ports L is a sliding fit 75 in the parallel part of the part M and a short conical face corresponding to the chamber of the part M extends from the reduced parallel part to the full outer diameter of the valve K. The valve K is arranged to extend over and slide upon the cylindrical outer surface of the lower part 80 of B and forms a chamber surrounding the jet orifice P. This chamber is connected directly with the air space in the top of the float chamber A by an air passage S passing through the body of the part B into the waist of the plug C and thence through the wall of the float chamber A. A passage J connects the lower part of the float chamber A and the lower part of the cylindrical bore of B. It follows from this construction that the pressure in the upper part of the float chamber is equal to that in the chamber 85 surrounding the fuel jet orifice and therefore the pressure of the fuel at the jet orifice is constant and independent of the varying suction of the engine.

A lever N pivoted at O is caused by the tension of a spring E to bear upon the upper end of the push rod D.

The tension of this spring may be varied by any known construction, such as a control wire F. In the modification shown in Figure 2 the spring R acts directly upon 105 the piston-shaped head G without the inter-

vention of the lever N and the push rod D. The operation of the device is as follows:—

When the throttle valve T is closed the valve K is seated on the part M and the needle valve H closes the orifice P by gravity and the pressure of the spring.

On slightly opening the throttle valve T, engine suction causes the valve K to rise and open the needle valve H, thus permitting fuel to flow to the interior of the valve K as soon as the lower parallel part of the valve is raised clear of the part M, while air is sucked through the annulus between the two conical surfaces of the valve and the part M respectively and is mixed with the fuel which flows from the interior of the valve K through the ports L. An initial adjustment of the part M is necessary in order to obtain the best setting of the relative positions of the valve K and the needle valve H, but when this is obtained the part M is secured from further movement. It will be seen that further opening of the throttle T will result in a higher mean position of the automatic valve K with a corresponding effect on the needle valve. Proper proportioning of the needle valve, together with the fact that the pressure of the fuel is independent of the effects of en-

gine suction, will therefore ensure the delivery of exactly the correct quantity of fuel for the amount of air sucked in.

As the ports L are situated in the narrowest part of the passage for the incoming air it will be seen that the greatest possible reduction of pressure existing in the carburetor is available for the atomization of the fuel.

Having now described my invention, what I claim as new and desire to secure by Letters Patent is:—

A carburetor of the type described including in combination a mixing chamber, a throttle valve between the engine and said mixing chamber, a constant level float chamber sealed from the atmosphere, a jet orifice below the level of the fuel in said float chamber, a loaded combined air and fuel valve adapted to be opened by engine suction through said throttle valve, fuel ports in the lower part of said combined valve at the position of greatest restriction of air entering the mixing chamber, and a passage connecting the area surrounding and acting upon the fuel jet with the upper part of said float chamber.

In testimony whereof I have signed my name to this specification.

FRANK HADFIELD ARNOTT.
